UNITED STATES PATENT OFFICE.

C. WESLEY HARMAN, OF NEW YORK, N. Y.

WATCH-CASE.

SPECIFICATION forming part of Letters Patent No. 313,326, dated March 3, 1885.

Application filed July 18, 1884. (No model.)

To all whom it may concern:

Be it known that I, C. WESLEY HARMAN, of the city of New York, in county and State of New York, have invented a new and useful Improvement in Watch-Cases, of which the following is a specification.

My invention has for its object a construction of watch-case which combines the advantages of neatness, strength, and dust-proof qualities with great compactness in direction of thickness and important economy in manufacture. For this purpose I cause the movement-ring to project beyond one edge of the case-center, and form on such projecting portion one or more screw-threads for attachment of as many caps, as hereinafter set forth.

In the accompanying drawings, Figure 1 is an axial section on line 1 1 of a watch-case embodying my invention in its preferred form. Fig. 2 is a rear view of the same without the back. Figs. 3, 4, 5, and 6 show modifications of my improved case.

A may represent an annular piece of metal, which combines the functions of case-center and bezel or inner front cap. A rabbet, *a*, in the inner rear margin of annulus A receives flange *b* of movement-ring B, which ring is inserted at the rear opening of said annulus, and when thus inserted has a portion, C, which projects rearward from the said case-center, and has an exterior screw-thread, *c*, for the corresponding screw-thread, *d*, on the concave or inner periphery of the back D, which, when screwed home, seats upon the rear shoulder, *a'*, of said case-center or annulus A.

For watches employing an inner back or inner rear cap, E, an additional screw-threaded step, *c'*, and shoulder *c''* enable dust-proof attachment of such inner back having a corresponding interior screw-thread, *e*, which back, when driven home, seats upon said shoulder *c''*.

F are half-head screws, which enable retention of the movement-ring within the case.

Circumferential shift of the movement-ring is prevented by one or more spurs, G, which oc-

cupy corresponding notches, *a''*, in the case-center.

The above-described preferred form of my improvement is susceptible of various modifications. For example, the screw-thread for the rear cap may be formed on the inner margin of the movement-ring, as at *c'''*, Fig. 3, the cap-margin being exteriorly screw-threaded, as at *e* in said figure. Such movement-ring may be formed for application of a single back without an inner back, as in Fig. 4. Such movement-ring and attached back may be associated with a case-center having a separable front or bezel, either with front cap, as in Fig. 5, to form a hunting-case, or with a bezel only for an open face.

The improvement may be used with cases whose pendant constitutes the usual projection from the case-center, or with cases in which the pendant is a projection from the movement-ring and occupies a notch in the case-center, as at J, Figs. 1 and 2. Finally, the movement-ring may be combined with a case-center formed in one integral piece with the back, as in Fig. 6, its protruding screw-threaded portion being then in front, as at *c^{IV}*, for dust-proof attachment of a corresponding screw-threaded bezel, K, as in said figure.

I claim herein as new and of my invention—

1. In a watch-case in which the center and one of the caps are formed in one piece, the other cap secured to the movement-ring and seating upon the case-center, substantially as set forth.

2. In a watch-case in which the center and bezel are formed in one piece, the back screwing onto the movement-ring and seating upon the case-center, substantially as set forth.

In testimony of which invention I hereunto set my hand.

C. WESLEY HARMAN.
